UNITED STATES PATENT OFFICE

1,969,345

PLUG CONNECTER

Edward F. Andrews, Chicago, Ill.

Application July 10, 1930, Serial No. 466,946

2 Claims. (Cl. 173—334)

This invention relates in general to connectors adapted to be removably inserted or plugged in domestic electric lighting outlets for supplying energy to electrical apparatus, and has more 5 particular reference to such a connector for conveniently connecting radio sets to the electric outlets.

A primary object of the present invention resides in the provision of a novel connector adaptable for conveniently connecting a radio receiving set with a power supply source, and which will provide convenient terminals or binding posts for the ground and antenna connections of the radio set.

15 An important object of this invention is the provision of a novel connector device or member for "plugging" in an electric outlet, which will permit the use of a minimum number of separate connections extending to a radio receiving 20 set.

Another important object of the invention is the provision of a novel connector having a plug member and a socket connectible with electric outlets, which prevents connecting the plug member 25 into the socket member in any but a predetermined manner.

A further important object of the invention is the provision of such a connector for "plugging" in an electric outlet that provides a socket for 30 receiving an electric outlet plug and a plug member to connect said electric outlet with a plurality of electrically operated devices.

Other objects and advantages of the invention will be apparent from the following description 35 and from the accompanying drawing, in which similar characters of reference indicate similar parts throughout the several views.

In the drawing:

Figure 1 is an elevation of a domestic electric 40 outlet provided with a socket member embodying some of the features of the invention; and

Figure 2 is a side elevation of the connector shown in Figure 1, connected to a radio receiving set.

45 Briefly, the invention contemplates the provision of a double socket member having terminal or contact leaves projecting from an end thereof, and receivable in an electric outlet for connecting the electric outlet to a plurality of terminals or contacts concealed within the body of the socket. Another terminal or contact is connected internally of said socket to a binding post projecting from one side of the socket and still another terminal is connected to another binding post projecting from the other side of the socket. This

socket is provided with an outlet adapted to accommodate a usual outlet plug for supplying current to electrical devices.

The terminals or contacts concealed within the socket are adapted to make contact with a plurality of plugs projecting from an end of a connector plug member and receivable in terminal holes or slots extending longitudinally of the socket, and these plugs are connected within the plug member to a plurality of conductors which 55 may extend to any electrically operated apparatus for supplying current thereto.

While the connector plug of the invention is adapted for general use as a means for connecting electrically operated apparatus to an electric outlet, it is particularly useful in connecting radio receiving sets to such outlets. The invention is, therefore, described hereinafter as applied to a radio receiving set. The usual radio receiving set employs a cable through which power or energy 70 may be supplied to the set, a separate antenna conductor not incorporated in the cable, and a separate ground conductor.

The present invention provides a connector which permits running all of these conductors in 75 a single cable to the radio set, and contemplates further the provision of a plurality of the sockets to be positioned in different electric outlets scattered over the house, wherever it is desired to operate a radio receiving set. By so providing 80 these sockets in the desired electric outlets, only a single plug will be required to connect the radio set to any desired socket, thereby permitting 85 changes in the location of the radio receiving set.

It will be understood, of course, that separate 90 antenna and ground connections may be made to each socket or a common antenna and ground connection may be made to ground and antenna leads of a plurality of sockets variously located 95 within the house.

For the accomplishment of the foregoing objects, the drawing shows conventional electric outlets 11, mounted on a wall 12 by means of outlet mounting plates 13, and a novel socket, generally designated by the reference character 14. 100 Each socket 14 for the purpose of making electrical connections with the outlets 11 is provided at one end with the usual terminal leaves or contacts 15, which are adapted to be received in recesses or slots in the outlet 11 and to securely 105 hold the socket in place when so "plugged" in the outlet. The sockets 14 may be made from molded hard rubber composition or any other suitable insulating material which is non-absorptive.

110 The terminals or leaves 15 are connected, as

illustrated at 16 in Figure 1, within the socket 14 to terminal contacts extending within the terminal holes or slots 17 and 18, formed longitudinally in the socket 14. Suitable binding posts or terminals 19 and 21 project from opposite sides of the socket 14, and are connected as shown at 22 within the body to terminal contacts, not shown, extending within the terminal holes 23 and 24, formed in the socket 14 parallel to the terminal holes 17 and 18.

The terminal or binding post 19 is adapted for connection with a conductor 25, which is connectible with the antenna of a radio receiving set 20, and the terminal 21 may be connected with a conductor 26 connectible with ground.

A connector plug member 27 is provided to cooperate with the sockets 14 for connection through a cable 28 to electrically operated apparatus, and for this purpose is provided with a plurality of plugs or terminals 29 and 31, receivable in the terminal holes 17, 18, 23 and 24 of each socket 14 and connected to wires or conductors 32 of the cable.

The invention contemplates constructing this separable two-part connector plug so that it will not be possible to plug the plug member 27 into the socket 14 in an improper manner, thereby assuring predetermined connections and polarity. To this end, the terminal holes 17 and 18 are formed to receive the plugs or terminals 29 and have a smaller diameter than the plugs or terminals 31, so that these plugs 31 and the wires in the cable 28 connected thereto may be connected only to the socket terminals or contacts within the terminal holes 23 and 24.

As already mentioned, the socket contacts or terminals in the terminal holes 17 and 18 are connected internally of the socket 14 to the leaves 15 for receiving electrical energy from the outlet 11, and the plugs 29 are adapted to contact with these terminals within the terminal holes 17 and 18. When the connector plug is used with a radio receiving set, these plugs 29 connect with wires 32 for supplying current to the filaments of the amplifier, detector, and power tubes, and to the rectifier plate. The plugs 31 receivable in the terminal holes 23 and 24 may connect with the ground and antenna terminals 18 and 19, respectively, and may be connected through the cable to the input of the amplifier, as will readily be understood by one skilled in the art.

It is sometimes desirable to use an electric outlet supplying energy to a radio set to supply current to other electrically operated devices without disconnecting the set. For this purpose the socket 14 is formed with a plug receiving outlet 33 to accommodate a usual outlet plug 34 for connection by means of a cable 35 with such devices. The outlet plug 35 has the usual contact leaves 36 receivable in terminal holes 37 for connection, as illustrated at 38, with the leaves 15. Thus the

socket 14 may be used to connect the outlet 11 to a radio set by means of the connector plug 27 and to other electrical devices by means of the outlet plug 34.

The connector of the invention prevents improperly connecting a radio set to its power supply and permits the use of a minimum number of conductors extending to the set. By the use of such a connector, a convenient ground and antenna terminal is provided in a compact plug member so that the external connections of the radio receiving set are concentrated at a given location, thereby facilitating the rapid connection of the set for use.

The connector of the invention avoids the unsightly antenna and ground leads usually connected to the receiving set by means of separate conductors, and provides in place thereof a single cable including the energy supply leads and the ground and antenna conductors.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States is:

1. In combination, a plug having a pair of projecting prongs adapted to enter sockets of a standard household power outlet, said plug being provided with a face having a pair of sockets connected to said prongs, terminals on said plug for the connection of a ground and antenna thereto, a second pair of sockets in said face connected to said connecting terminals, and a plug associated with a radio receiving set having four prongs adapted to cooperate with the sockets of the face of the first said plug, the prongs of the last said plug being connected to power, antenna and ground conductors of the set.

2. In combination, a plug having a pair of projecting prongs adapted to enter sockets of a standard household power outlet, said plug being provided with a pair of faces each having a pair of sockets connected to said prongs, one of said faces having its sockets arranged for cooperation with the prongs of a standard household plug, terminals on first said plug for the connection of a ground and antenna thereto, a second pair of sockets in the other face connected to said connecting terminals, and a plug associated with a radio receiving set having four prongs adapted to cooperate with the sockets of the last said face of the first said plug, the prongs of the last said plug being connected to power, antenna and ground conductors of the set.

EDWARD F. ANDREWS.
